APPARATUS FOR ASSEMBLING HEEL-LIFTS
AND RANDS

John B. Hadaway, Swampscott, Mass., assignor
to United Shoe Machinery Corporation, Paterson, N. J., a Corporation of New Jersey

Application December 15, 1930. Serial No. 502,400

23 Claims. (Cl. 12—67.1)

This invention relates to apparatus by which such portions of shoe-heels as lifts and rands may be secured to each other, as by forcing together surfaces of these elements to which adhesive coatings have been applied.

A convenient manner of attaching to heel-lifts or bases the rands which are to fill the peripheral spaces between the plane heel-surfaces and the curved heel-seats is by means of an interposed adhesive. Latex is especially suitable for this purpose, since the surfaces to be opposed may be coated, allowed to become sufficiently dry to be handled, and then the attachment accomplished by pressure upon the pieces associated with their coated surfaces in contact. This is as disclosed in Letters Patent of the United States No. 1,779,368, Cavanagh, October 21, 1930. An object of my invention is to provide for the assembling of the previously coated heel-portions by means simple in structure and rapid and efficient in action. This object I attain by combining a roll having a conical lift-engaging surface and a roll having a conical rand-engaging surface, these rolls being rotated and having associated with them a lift- and rand-gage, from which gage the rolls decrease in diameter outwardly. Means, as a spring variable as to its force, is illustrated for urging one of the rolls yieldably toward the other. The conical rolls will not only act, because of the gradually increasing speeds of rotation of their peripheries considered longitudinally of their axes, to turn a lift and associated rand, but also, by properly proportioning the rolls to the curvature of the lift, the slant-heights of the conical surfaces from the bases to the apices of the complete cones being less than the radius of curvature of said lift, the work may be held against the gage with little or no effort on the part of the operator. This action may be augmented by an arrangement of the work-engaging surface of one of the rolls, preferably that which acts upon the lifts. This roll-surface is shown as provided with projections inclined rearwardly, with respect to the direction of rotation, from the portion of the roll of smaller diameter toward the larger portion or base. These projections apply to the work both a feeding or advancing force exerted circumferentially of the roll and a force in the direction of the gage. In the present embodiment of the invention, the projections are formed between inclined grooves and are intersected by circumferential grooves which tend to prevent the heel-portion from slipping outwardly from the gage. I prefer to have the rolls so

related that, at their lines of contact with the work, they diverge in the same direction as do the opposite surfaces of the lift and rand, the latter being beveled. This angle, however, is best less than that between the opposite work-surfaces, 60 thus producing a greater pressure at the exterior of the heel and insuring perfect contact between the lift and rand where it is most essential. The gage, which may be variable in position, has, as herein disclosed, independent lift- and rand-contact-surfaces lying in different planes, the rand-contact-surface being farther from the center of the lift. The rand is thereby caused to project beyond the lift with which it is assembled, insuring the proper relation of the rand for 70 the succeeding step of compressing the heel. I guard against tendency of the assembled elements to assume a dished form, or one generally outwardly curved at the outer surface of the lift, by making the work-engaging portion of 75 maximum diameter of one of the rolls, preferably that contacting with the rand, greater than the corresponding portion of the associated or lift-contacting roll and being farther removed from the center of the lift. By so doing, particularly when greater pressure is applied to the outer portion of the work by the roll-surfaces diverging at a less angle than the opposite work-surfaces which they engage, the periphery of the lift is bent in a direction neutralizing the 85 previously mentioned distortion. Herein, the yieldable roll is shown as rotatable in a pivoted arm, the work-gage being movable with said arm. Therefore, to prevent variation in the spacing of the work-contacting surfaces of the gage 90 from the associated roll, said surface is preferably curved about the pivotal axis of the arm.

The accompanying drawings illustrate a particular embodiment of the invention and a modification thereof in one respect,

Fig. 1 being a broken side elevation of my improved assembling apparatus;

Fig. 2, a detail in side elevation showing the relation of the assembling rolls to each other and to the work;

Fig. 3, a similar view of another arrangement of the rolls and including associated elements;

Fig. 4, an end elevation looking from the left of Fig. 1;

Fig. 5, an enlarged view taken in the same 105 direction as Fig. 4 but including only the lower roll and more closely associated parts;

Fig. 6, a plan view of said lower roll; and

Fig. 7, a perspective view of a lift and rand assembled by the apparatus.

95

100

110

In the upper portion of a frame 10, adapted, as illustrated, to be supported upon a bench, is journaled a horizontal shaft 12 rotated from a main driving shaft 14 by spur-gearing 16. At 5 its forward extremity, the shaft 12 acts through bevel-gearing 18 to rotate in the frame a downwardly and outwardly inclined shaft 20 having secured to its lower end a roll 22. This roll is conical in form, decreasing gradually in diameter outwardly, but preferably with its reduced portion omitted, being, therefore, frusto-conical. The roll 22 is one of a pair of work-feeding and pressure-rolls, the companion roll 24 of the pair being also frusto-conical, with its 10 smaller end outward and being fast on the upper extremity of an upwardly and outwardly inclined shaft 26 journaled in a bracket 28. The apex of the conical surface of the roll 24 preferably lies in proximity to that of the roll 22, and it is rotated through bevel-gearing 30 from a shaft 32 turning in an arm 34 pivoted at 36 upon the frame and upon which the bracket 28 is mounted. A chain of spur-gears 38 connects the shaft 32 to the shaft 12. The driving connections and 15 diameters of the conical surfaces are such that opposite points upon the latter travel at approximately the same speed. The roll 22, being fixed against bodily movement, acts as an abutment-roll, while the lower work-supporting roll 20 may be yieldable by virtue of movement of its arm 34. This yield is, in the present instance, 20 against the resistance of a spring 40 interposed between a depending portion 42 of the arm 34 and a screw 44 threaded horizontally into the 25 frame. The spring surrounds and is retained against lateral displacement by a rod 46 pivoted to the arm-portion 42 and guided in a bore in the screw. Said screw is adjustable in position, to allow the expansive force of the spring to be 30 varied, by a hand-wheel 48. The normal space between the work-engaging surfaces of the rolls 22 and 24 may be altered by an adjustable stop-screw 50 mounted for vertical movement in the 35 frame and against which the spring 40 urges the arm 34. As illustrated, the screw 50 is threaded into a bushing 52 in the frame and may be turned by a hand-wheel 54 splined upon the upper end of the shaft and with its notched under side normally held by a spring 56 against a retaining projection 58 upon the frame. 40

At the inner side of the rolls 22 and 24 is a work-gage 60 carried by a bracket 62 joined to the frame 10 by a slot-and-screw connection 64, permitting the gage to be positioned at different 45 distances from the rolls and thus determine their engagement with the work. For the operation of the apparatus upon heel-lifts *H* and rands *R*, the gage is provided with a lift-contact-surface 66 and a rand-contact-surface 68; and, since it 50 is convenient for the operator to present these heel-portions to the rolls with the lift down, the first-mentioned gage-surface is below the companion surface. Both surfaces are appropriately inclined to receive the engagement of the outer edges of the associated lift and rand as they are presented to the rolls, and preferably lie in different planes, the surface 68 being outside the surface 66 or farther removed from the rolls. It is advantageous to have the gage-surface 55 60 curved about a center lying at the pivotal axis of the arm 34. This causes the distance between this surface and the roll 22 to remain the same, whatever the angle of the arm. The gage-arrangement allows the rand, after assembly, to project beyond the lift. This is important, be-

cause the surfaces of a rand are so related that when it is applied to a lift the lower edge of the rand will project beyond the upper; see Figs. 2 and 3. The arrangement of the gage-surfaces will cause the upper edge of the rand to lie far enough out to insure it coming in the finished surface of the heel, without leaving an unsightly depression. The projecting lower edge is removed in the trimming of the heel. There is shown, mounted upon the bracket 62 with the gage 60, a guard consisting of opposite sections 70 and 72 secured, respectively, to the front and rear sides of the bracket by slot-and-screw connections 74. Each section has a curved arm 76 embracing a portion of the roll 24 and its bevel-gear 30, and a depending arm 78 partially surrounding the associated bevel-gear. The guard prevents contact of the operator's hands with the lower roll and its gearing. Its variable attachment to the bracket 62 enables the guard to be positioned correctly with respect to the elements which it surrounds, regardless of the adjustment of the bracket at 64. 80

For assembling a heel-lift and a rand by the pressure of the rolls 22 and 24 upon them with the lift below the rand, I prefer to so mount the roll 24 that the upper portion of its conical work-engaging surface, along a line directly opposed by an element of the upper roll, is approximately horizontal. This gives a surface located similarly to the customary work-supporting table, and one over which the operator may readily introduce the plane lower face of a lift. The corresponding portion of the conical surface of the upper roll is best so held by its mounting that it 100 diverges from its companion toward the gage 60 or from the end of smaller to that of greater diameter, approximately corresponding in inclination to the angle between the upper surface of the beveled rand and the lower surface of the 105 associated lift. As may best be seen in Fig. 3, this coincidence of inclination is not exact. It is important that the adhesion of the rand and lift shall be most perfect at the outside of the heel, where the joint will be visible in the finished work. Consequently, in the illustrated embodiment of the invention, the angle between the opposite elements of the conical surfaces, or at the bite of the rolls, is somewhat less than between the outer surfaces of the rand and lift. 110 This results in greater pressure upon the work toward the periphery and the desired firm adhesion. It also, by the maximum separation between the inner portions of the conical surfaces, gives a space sufficient to receive the thin edge 115 of the rand as it crimps in bending. On the other hand, these inner surfaces are close enough together to retain the crimped edge from projecting beyond the plane of the thick edge of the 120 rand. 125

Under certain conditions, when thin lifts are being operated upon, as when the operator, by pressure upon the lifts during their presentation to the apparatus, distorts them, the assembled parts may become convex, the lift being dished outwardly. The lift tends to be held in this form by the applied rand, and it becomes impossible to perfect the shape of the finished heel by its compression. This I overcome by the arrangement of rolls particularly illustrated in Fig. 2 of the 130 drawings. Here the rolls 22 and 24 are of different diameters at their bases, the outer edge of the roll 22 projecting beyond its companion. It thus lies farther from the center of the lift being 135 operated upon, extending beyond the plane of 140

145

150

the gage-surface 66 close to the surface 68. This, particularly with the greater pressure exerted by the rolls at the outside of the rand, as just indicated, tends to bend the projecting edge of the 5 rand over the lift, setting up, when the parts are secured together, stresses opposite to the deforming forces and counteracting these. The outer surface of the lift therefore remains substantially plane. It is not always necessary to employ this 10 arrangement, the organization of Fig. 3, in which the roll-surfaces are substantially the same length along the body, being satisfactory for thicker lifts. In fact, the pressure upon the edge of the rand, protruding beyond the lift, forces 15 this edge below the upper surface of said lift, and produces, to some extent, the same compensating effect.

The conical form of the rolls is caused to relieve the operator of almost all effort in holding the 20 work against the gage 60. Since the work-engaging surfaces of the rolls rotate at progressively greater speeds from the inner portions toward the outer, because of the gradual increase in diameter, the work will move in a curved path, the 25 center of which is toward the center of the lift and rand. By employing, as is shown herein, rolls the slant-heights of the conical surfaces of which have a less length between the apices and bases than the radii of curvature of the lifts and rands, 30 the work is urged against the gage and there held as it advances, and, as opposite points at the bite of the rolls are moving at substantially the same speed, there is no tendency to displace the work-pieces by slipping one over the other. Rands or 35 ordinarily come to the apparatus either practically straight from end to end or partly formed to the horseshoe-shape which they must assume when assembled with heel-lifts. In their unconnected condition, as a rand is pressed against a lift by the 40 rolls 22 and 24, the resilience of the rand as it contacts with the gage-surface 68 exerts a force tending to separate the associated lift from the gage-surface 66. To assist the conical rolls to 45 overcome this, the lift-engaging surface of the roll 24 has formed in it a circumferential series of projections 80 between grooves 82. These projections may be of the same form and extend in a regular series about the roll between its ends. Because of the progressive difference in the 50 circumferences of the roll-surface, both the projections and grooves are tapered longitudinally from the portion of smaller to that of greater diameter. Each projection, instead of coinciding in direction with an element of the conical surface, is 55 inclined toward the base of the roll rearwardly with respect to its rotation. As a result of this inclination, the force applied to a lift at any point along a projection may be considered as including a component acting circumferentially to feed 60 and rotate the engaged lift and a force exerted radially with relation to the work, the effect of which is to press the edge of the lift against the gage-surface 66. The continued engagement between the lift and gage is thus perfectly maintained. As an additional guard against the outward displacement of the lift, a series of circular 65 grooves 84 may be formed about the work-engaging surface of the roll 24. This divides each of the 70 projections 80 into a series of projections lying between the ends of the roll and resisting movement of the lift. I have shown the rand-engaging surface of the roll 22 as provided with a circumferential series of projections 86 substantially coinciding with the elements of the con-

ical surface. These act upon the rand to effectively feed it forward.

In using the apparatus of this invention, the operator takes a lift H and a rand R having a coating of some such adhesive as latex upon their faces which are to be secured together, places them in the proper relation at the breast-corner a of the lift (Fig. 7) and introduces them over the horizontal surface of the lift-engaging roll 24, the outer edges of the lift and rand contacting, respectively, with the gage-surfaces 66 and 80 68. In doing this, the arm 34 is pressed down against its spring 40. The operator then permits the spring to force the roll 24 against the lift, and therefore the rand against the engaging surface of the roll 22. The pressure at once unites the coated pieces, this continuing as rotation of the rolls feeds the work forward in a curved path and holds it against the gage under the influence of the conical work-engaging surfaces and the force exerted by the inclined projections 80. A tight joint at the outside of the work-pieces is assured by the greater pressure at the portions of the rolls of maximum diameter. This pressure applied to the edge of the rand by 100 the roll 22, extending at its base-portion beyond the companion roll, so forces said rand outward and downward over the lift that convexity of the outer surface of the latter is prevented. Travel of the work continues until the breast-corner b is 105 reached, when it is ejected from the rolls, the uniting of the lift and rand being completed.

Having described my invention, what I claim as new and desire to secure by Letters Patent of the United States is:

1. An apparatus for assembling heel-lifts and rands comprising a rotatable roll having a conical lift-engaging surface, a co-operating rotatable roll having a conical rand-engaging surface, means for rotating the rolls and a lift- and rand-gage associated with the rolls, both of said rolls decreasing in diameter outwardly from the gage. 115

2. An apparatus for assembling heel-lifts and rands comprising a rotatable roll having a conical lift-engaging surface, a co-operating rotatable roll having a conical rand-engaging surface, means for rotating the rolls in opposite directions, opposite work-contacting points of the two rolls traveling at substantially the same speed, 120 and a lift- and rand-gage associated with the rolls. 125

3. An apparatus for assembling heel-lifts and rands comprising a gage, rotatable rolls receiving the work between them, and means for rotating the rolls, said rolls being constructed and arranged to urge against the gage both the lift and rand being operated upon. 130

4. An apparatus for assembling heel-lifts with curved peripheries and rands comprising a rotatable roll having a conical lift-engaging surface, a co-operating roll having a conical rand-engaging surface, the slant-height of the conical surfaces of the rolls to the apices being less than the radius of curvature of the lifts, means for rotating the rolls in opposite directions, and a lift- and rand-gage associated with said rolls. 135

5. An apparatus for assembling heel-lifts and rands comprising a rotatable roll having a conical lift-engaging surface, a co-operating rotating roll having a conical rand-engaging surface, the line of contact between the lift-engaging roll and a lift being approximately horizontal and the line of contact between the rand-engaging roll and a rand being inclined to the horizontal, 145 150

- means for rotating the rolls in opposite directions, and a lift- and rand-gage associated with the rolls, both of said rolls decreasing in diameter outwardly from the gage.
6. An apparatus for assembling heel-lifts and beveled rands comprising a rotatable roll having a conical lift-engaging surface, a co-operating rotatable roll having a conical rand-engaging surface, the rolls at their lines of contact with the work diverging in the direction of the periphery of the lift, and means for rotating the rolls.
7. An apparatus for assembling heel-lifts and beveled rands comprising a rotatable roll having a conical lift-engaging surface, a cooperating rotatable roll having a conical rand-engaging surface, the rolls at their lines of contact with the work diverging in the same direction as do the opposite surfaces of the lift and rand but at a less angle, and means for rotating the rolls in opposite directions.
8. An apparatus for assembling heel-lifts and rands comprising a rotatable roll having a conical lift-engaging surface, a co-operating rotatable roll having a conical rand-engaging surface, means for rotating the rolls, and a gage associated with said rolls and provided with lift- and rand-contact-surfaces lying in different planes.
9. An apparatus for assembling heel-lifts and rands comprising a rotatable roll having a conical lift-engaging surface, a co-operating rotatable roll having a conical rand-engaging surface, means for rotating the rolls, and a lift- and rand-gage associated with said rolls, the work-engaging portion of maximum diameter of one of the rolls being greater than the corresponding portion of the associated roll and both of said maximum portions being at the ends toward the gage.
10. An apparatus for assembling heel-lifts and rands comprising a rotatable roll having a conical lift-engaging surface, a co-operating rotatable roll having a conical rand-engaging surface, means for rotating the rolls, a gage associated with said rolls and provided with lift- and rand-contact-surfaces lying in different planes, and means arranged to vary the position of the gage toward and from the rolls.
11. An apparatus for assembling heel-lifts and rands comprising a rotatable roll having a conical lift-engaging surface, a co-operating rotatable roll having a conical rand-engaging surface, means for rotating the rolls in opposite directions, and a gage associated with said rolls and provided with lift- and rand-contact-surfaces lying in different planes, the rand-contact-surface of the gage being farther from the center of the lift than is the lift-contact-surface.
12. An apparatus for assembling heel-lifts and rands comprising a rotatable roll having a conical lift-engaging surface, a co-operating rotatable roll having a conical rand-engaging surface, means for rotating the rolls in opposite directions, and a lift- and rand-gage associated with said rolls, the work-engaging portion of maximum diameter of the rand-roll being greater than the corresponding portion of the lift-roll.
13. An apparatus for assembling heel-lifts and rands comprising a rotatable roll having a conical lift-engaging surface, a co-operating rotatable roll having a conical rand-engaging surface, means for rotating the rolls in opposite directions, and a gage associated with said rolls and provided with lift- and rand-contact-surfaces lying in different planes, the work-engaging portion of maximum diameter of the rand-roll extending beyond the plane of the lift-contact surface of the gage into proximity with the rand-contact-surface.
14. An apparatus for assembling heel-lifts and rands comprising a rotatable roll having a conical lift-engaging surface, a co-operating rotatable roll having a conical rand-engaging surface, means for rotating the rolls in opposite directions, and a gage associated with said rolls and provided with lift- and rand-contact-surfaces lying in different planes, the rand-contact-surface of the gage being farther from the center of the lift than is the lift-contact-surface, the work-engaging portion of maximum diameter of the rand-roll extending beyond the plane of the lift-contact-surface of the gage into proximity with the rand-contact-surface.
15. An apparatus for assembling heel-lifts and rands comprising co-operating rotatable rolls having respectively conical lift- and rand-engaging surfaces, means for rotating the rolls in opposite directions, and a gage associated with the rolls, one of said rolls being provided upon its work-engaging surface with projections inclined rearwardly with respect to the direction of rotation from the portion of the roll of smaller diameter toward the larger portion.
16. An apparatus for assembling heel-lifts and rands comprising co-operating rotatable rolls having respectively lift- and rand-engaging surfaces, means for rotating the rolls in opposite directions, and a gage associated with the rolls, the lift-roll being provided with projections arranged to urge the work toward the gage.
17. An apparatus for assembling heel-lifts and rands comprising a gage, co-operating rotatable rolls having respectively conical lift- and rand-engaging surfaces, and means for rotating the rolls in opposite directions, the lift-roll being provided with grooves extending between its extremities along its work-engaging surface and inclined rearwardly with respect to the direction of rotation from the portion of the roll of smaller diameter toward the larger portion.
18. An apparatus for assembling heel-lifts and rands comprising a gage co-operating rotatable rolls having respectively conical lift- and rand-engaging surfaces, and means for rotating the rolls in opposite directions, the lift-roll being provided with grooves extending between its extremities along its work-engaging surface and inclined rearwardly with respect to the direction of rotation from the portion of the roll of smaller diameter toward the larger portion and circumferential grooves intersecting the inclined grooves.
19. An apparatus for assembling heel-lifts and rands comprising a rotatable roll having a conical lift-engaging surface, a co-operating rotatable roll having a conical rand-engaging surface, means arranged to yieldably force one of the rolls toward the other, means for rotating the rolls in opposite directions, and a lift- and rand-gage associated with said rolls.
20. An apparatus for assembling heel-lifts and rands comprising a frame, an arm pivoted thereon, a pair of conical lift- and rand-engaging rolls rotatable in the frame and arm, and means acting upon the arm and arranged to force its roll yieldably toward the companion roll.
21. An apparatus for assembling heel-lifts and rands comprising a frame, an arm pivoted thereon, a pair of conical, lift- and rand-engaging rolls rotatable in the frame and arm, a variable stop for the arm, a spring arranged to force the

arm against the stop, and means arranged to vary the force of the spring.

22. An apparatus for assembling heel-lifts and rands comprising a frame, an arm pivoted thereon, a pair of conical lift- and rand-engaging rolls rotatable in the frame and arm, means acting upon the arm and arranged to force its roll yieldably toward the companion roll and a gage carried by the arm and having a work-contacting surface curved about the pivotal axis of the arm.

23. An apparatus for assembling heel-lifts and

rands comprising a frame, an arm pivoted thereon, a pair of conical lift- and rand-engaging rolls rotatable in the frame and arm, means acting upon the arm and arranged to force its roll yieldably toward the companion roll and a gage carried by the arm and having a work-contacting surface curved about the pivotal axis of the arm. 80
